United States Patent Office

Des. 192,926
Patented May 29, 1962

192,926

TELEPHONE STAND

James E. Simpson, 1131 W. Santa Barbara St.,
Los Angeles, Calif.

Filed Oct. 23, 1961, Ser. No. 67,196

Term of patent 14 years

(Cl. D33—3)

FIG. 1 is a perspective view of a telephone stand showing my new design;

FIG. 2 is a side elevational view thereof;

FIG. 3 is a rear elevational view thereof; and

FIG. 4 is a plan view thereof.

The dominant features of my design reside in those portions shown in full lines on the drawing.

I claim:

The ornamental design for a telephone stand, substantially as shown and described.
